UNITED STATES PATENT OFFICE.

GEORGE K. HANNAH, SAMUEL M. TILTON, AND MATTI KAARLELA, OF FITCHBURG,
MASSACHUSETTS.

BOBBIN-STRIPPING MACHINE.

Application filed June 29, 1921. Serial No. 481,424.

To all whom it may concern:

Be it known that we, GEORGE K. HANNAH, SAMUEL M. TILTON, and MATTI KAARLELA, citizens of the United States, all residing 5 at Fitchburg, in the county of Worcester and State of Massachusetts, have invented a new and useful Bobbin-Stripping Machine, of which the following is a specification.

This invention relates to a machine for 10 removing waste yarn from bobbins which have been ejected by the weft replenishing mechanism of an automatic loom. It is common to provide weft detecting mechanism by which the weft replenishing mechanism 15 is called into operation just before the filling upon the active weft carrier is exhausted. The weft carriers or bobbins are thus ejected with a small amount of waste yarn thereon and it is necessary to remove this yarn before the bobbins can 20 be again used.

The removal of the yarn by hand is expensive and otherwise unsatisfactory, as the 25 yarn clings tightly to the bobbin and can hardly be removed manually except by cutting, which almost invariably injures the bobbin.

Machines have been heretofore designed 30 for removing the yarn from the bobbin by stripping the yarn lengthwise therefrom and it is the general object of our invention to provide an improved machine for this purpose, so designed that it will be efficient and reliable in operation and that it will require 35 very little attention from the operator.

With this general object in view our invention relates particularly to certain arrangements and combinations of parts to be hereinafter described and more particularly 40 pointed out in the appended claims.

A preferred form of our invention is shown in the drawings in which

Fig. 1 is a side elevation of our improved machine;

Fig. 2 is a detail plan view of a portion 45 of the hopper or magazine, looking in the direction of the arrow 2 in Fig. 1;

Fig. 3 is a left hand end elevation of the machine, taken in the direction of the arrow 50 3 in Fig. 1;

Fig. 4 is a perspective view of one of the weights used in connection with the movable stripping jaws;

Fig. 5 is an enlarged partial front elevation, looking in the direction of the arrow 55 5 in Fig. 3;

Fig. 6 is an end elevation of the waste ejector;

Fig. 7 is a front view thereof, looking in the direction of the arrow 7 in Fig. 6; 60

Fig. 8 is a plan view of the bobbin stripping mechanism;

Fig. 9 is a sectional end elevation, taken along the line 9—9 in Fig. 8;

Figs. 10, 11 and 12 are diagrammatic 65 views showing the operation of the machine, and

Fig. 13 is a diagrammatic view indicating the operation of the waste ejector.

Referring to the drawings, our improved 70 machine comprises a base 20 supported on legs 21. A magazine or hopper 22 is mounted above the base 20, said magazine being preferably formed as a curved segment and being inclined to feed the bobbins 75 by gravity toward the stripping devices. At its lower or front end, the magazine or hopper 22 communicates with guide plates forming a vertical passage 23 (Figs. 3 and 9) through which the bobbins move downward until the lowermost bobbin rests upon a series of supports 24, 25 and 26 (Figs. 8 80 and 9).

The supports 24 and 25 are pivotally connected to the lower ends of two-armed levers 85 27 and 28 fixed to a cross shaft 29 supported in bearings in a frame 30 secured to the base 20. The support 26 is pivotally connected to an arm 31 (Fig. 3) also secured to the shaft 29 and connected by a link 32 90 to a lever 33 pivotally mounted on the end of the frame 30.

A link 34 connects the lower arm of the lever 33 to the arm 35 of a bell crank 36 which is pivoted at 37 on the base 20. A 95 stop 38 limits rearward movement of the link 34 and a spring 39 holds the link 34 yielding against the stop.

The supports 24, 25 and 26 are thus normally held yielding in the position shown 100 in Figs. 8 and 9, in which position they prevent the escape of bobbins from the magazine passage 23.

Retaining rods 40 and 41 (Figs. 8 and 9) are pivotally connected to the upper ends 105 of the levers 27 and 28 and are in inopera-

tive position when the supports 24, 25 and 26 are in operative position. The supports 24 and 25 and the rods 40 and 41 are slidably supported at their outer ends by a plate 42 rigidly supported on the frame 30 and the support 26 is slideable in a block 43 (Fig. 3) secured to the end of the frame 30.

Reference to Fig. 9 will show that a clock-wise rocking movement of the shaft 29 will withdraw the supports and advance the rods, thus permitting the escape of a single bobbin from the magazine. Such rocking movement of the shaft 29 is caused by engagement of a roll 44 (Fig. 3) with the lower end of the bell crank 36. The roll 44 is mounted on the end of a wide-faced cam 45 fixed to a cam shaft 46 (Fig. 1) supported in bearings 47 extending downward from the base 20. The shaft 46 may be rotated in any convenient manner, as by a motor 48 positioned below the base 20 and connected by a belt 49 to a pulley 50 on a shaft 51. A pinion 52 on the shaft 51 engages a gear 53 on a shaft 54, which shaft is connected by beveled gears 55 and 56 to the cam shaft 46.

As the bobbin is released from the supports 24, 25 and 26 it falls upon a plurality of fixed hook-shaped stripping jaws 60, 61 and 62 (Figs. 8 and 9). Movable jaws 63, 64 and 65 are mounted upon separate pivots 66, 67 and 68 on the frame 30 and are connected by links 69 (Fig. 9) to separate cam-operated levers 70.

The levers 70 are loosely mounted upon a cross shaft 71 in the frame 30 and the L-shaped lower ends of the levers extend over the cam 45 in position for engagement therewith. Heavy weights 72 are mounted on the lower ends of the levers 70 and springs 73 connect two of the levers 70 to tension levers 74 pivoted at 75 on the leg 21 and engaging the lower face of the cam 45. No spring 73 is used in connection with the lever 70 which actuates the movable jaw 65 as this jaw engages the tip of the bobbin where slight pressure is required.

A yielding end stop or guide 76 (Figs. 1 and 3) is pivoted at 77 on the end plate of the passage 23. A light spring 78 holds the guide 76 yieldingly in the position shown in Fig. 1, in which position it locates the bobbin correctly for the operation of the stripping jaws. As the bobbin is thereafter ejected from the stripping mechanism, the guide 76 yields to permit the exit of the bobbin.

The mechanism thus far described provides for feeding the bobbins automatically and intermittently to the stripping jaws. After a bobbin is positioned and securely held between the jaws, it is forced endwise from the machine while the jaws at the same time strip the waste therefrom. This end-

wise ejection of the bobbin is caused by a plunger 80 (Fig. 1) slideable in bearings 81 mounted on the base 20 and connected at one end to a cross head 82 mounted to slide in guides 83. The cross head 82 is connected by a link 84 to a crank arm 85 on a shaft 86. A gear 87 on the shaft 86 meshes with the gear 53 in the gear train which drives the cam shaft 46.

The plunger 80 is preferably provided with a small projection 88 (Fig. 5) which enters the tip of the bobbin and prevents relative lateral displacement of the bobbin and plunger. A guide plate 89 (Fig. 1) is secured to the end of the base 20 and guides the ejected bobbin to a suitable receptacle 90.

The operation of the machine as thus far described is thought to have been clearly indicated in the detailed description thereof, and is further illustrated by the diagrammatic Figures 10, 11 and 12. As the cam shaft 46 rotates, it withdraws the bobbin supports and permits a single bobbin to fall upon the fixed jaws, at the same time advancing the rods 40 and 41 to hold back the next bobbin. At the time when the bobbin is thus placed on the fixed jaws, the levers 70 are held in raised position by the cam 45, thus raising and withdrawing the movable jaws 63, 64 and 65 to permit the insertion of the bobbin.

The levers 70 are then permitted to move downward under the influence of the weights 72 and springs 73, which place a heavy but yielding pressure upon the movable jaws. The plunger 80 thereupon advances, forcing the bobbin endwise from between the jaws. During this operation the jaws grip whatever waste there may be on the bobbin and prevent movement of the waste with the ejected bobbin. Under ordinary conditions the stripping operation is performed almost entirely by the pair of jaws 60 and 63 adjacent the butt of the bobbin but with certain types of bobbins the waste may extend nearly the entire length of the bobbin.

It is found that the waste thus stripped from the bobbins is liable to clog the machine during the continued operation thereof and accordingly we have made special provision for ejecting the waste. For this purpose we have provided the ejector shown in Figs. 5, 6 and 7, which ejector comprises a U-shaped frame 90 mounted on fixed pivots 91 (Fig. 5) having short upwardly projecting fingers 92 (Fig. 7). The frame 90 is connected by a link 93 to a bell crank 94 (Fig. 9) to which is connected a spring 95 which yieldingly holds the waste ejector in the position shown in full lines in Fig. 6. A cam roll 96 is mounted on one end of the cam 45 (Fig. 5) in position to engage the bell crank 94 and swing the waste ejec-

tor 90 to the position shown in dotted lines in Fig. 6 immediately after the ejection of each bobbin. Such movement of the ejector clears the waste from the fixed jaws, 5 as indicated in Fig. 13 and deposits the waste in a separate receptacle 97 (Figs. 1 and 3).

The machine thus described has been found in practical operation to show marked 10 advantages for the purposes designed and will strip the waste from the bobbins however tightly wound and will operate with a very small percentage of broken bobbins.

The machine may be easily adapted for 15 use in removing roving waste by slight changes in the dimensions of certain parts.

Having thus described our invention it will be evident that changes and modifications can be made therein by those skilled 20 in the art within the spirit and scope thereof as set forth in the claims and we do not wish to be otherwise limited to the details herein disclosed but what we do claim is:—

1. In a bobbin stripping machine having 25 bobbin feeding mechanism, in combination, a plurality of fixed supporting jaws, a plurality of movable jaws co-operating therewith to support a bobbin and guide the same axially, and means to force an oper- 30 atively positioned bobbin longitudinally from between said jaws.

2. In a bobbin stripping machine having 35 bobbin feeding mechanism, in combination, a plurality of fixed supporting jaws, a plurality of movable jaws co-operating therewith to support a bobbin and guide the same axially, means to positively remove said movable jaws from operative 40 position, means to yieldingly return said jaws to operative position, and means to force an operatively positioned bobbin longitudinally from between said jaws.

3. In a bobbin stripping machine having, 45 a plurality of fixed supporting jaws, a plu-

rality of movable jaws co-operating therewith to support a bobbin and guide the same axially in position, a hopper having a gravity feed toward said jaws, a plurality of bobbin supports, a plurality of bobbin retainers, and means for simultaneously moving said supports and retainers alternately to operative and inoperative positions, thereby presenting said bobbins singly to said jaws.

4. In a bobbin stripping machine, a plurality of fixed stripping jaws, a plurality of movable stripping jaws, and independent means for yieldingly advancing each movable jaw toward its associated fixed jaw to grip bobbin between said jaws.

5. In a bobbin stripping machine, jaws to support and grip a bobbin, means to eject a bobbin longitudinally therefrom, and mechanical means to positively remove the waste yarn from the jaws after the 65 bobbin has been ejected therefrom.

6. In a bobbin stripping machine, jaws to support and grip a bobbin, means to eject a bobbin longitudinally therefrom, and a transversely swinging frame effective to remove the waste yarn from said jaws.

7. In a bobbin stripping machine, a plurality of fixed jaws having recessed outer ends, a plurality of movable jaws co-operating therewith and having hook-shaped 75 outer ends, and means to yieldingly advance said movable jaws to engage a bobbin supported on said fixed jaws.

8. In a bobbin stripping machine having bobbin stripping means, a segmental 80 inclined hopper effective to feed bobbins to said stripping means and means to release bobbins singly from said hopper.

In testimony whereof we have hereunto affixed our signatures.

GEORGE K. HANNAH.
SAMUEL M. TILTON.
MATTI KAARLELA.
